United States Patent Office.

JOHN L. HADDEN, OF PHILADELPHIA, PENNSYLVANIA.

Letters Patent No. 77,280, dated April 28, 1868.

IMPROVED WATER-COOLER.

The Schedule referred to in these Letters Patent and making part of the same.

TO ALL WHOM IT MAY CONCERN:

Be it known that I, JOHN L. HADDEN, of the city of Philadelphia, in the State of Pennsylvania, have invented a new and useful Improvement in the Portable Sheet-Metal Water-Cooler; and I do hereby declare that the following is a full, clear, and exact description of the same, reference being had to the accompanying drawings, making a part of this specification, in which—

Figure 1 is a vertical central section of the lower end of the inner cylinder of a portable sheet-metal water-cooler, having my improvement applied thereto, and

Figure 2 a plane view of the bottom of the said cylinder—

Like letters of reference indicating the same parts when in both figures.

The object of my improvement is to render the sheet-metal bottom of the inner cylinder of a cooler secure against being broken through, cracked, indented, or otherwise injured by the dropping of the ice-lumps into the cylinder, in replenishing it; and my invention consists in corrugating the said bottom so as to give it the raised or general conical form, substantially as hereinafter described and set forth.

Referring to the drawings, A is the usual body or vertical sides of the inner cylinder of a cooler, and B the improved corrugated conical bottom of the same, the faint lines in fig. 1 indicating the usual external cylinder and foot-flange.

The bottom, B, is formed by taking a flat disk of the sheet metal, (usually sheet iron,) and, by means of a pair of stamping-dies, giving it the general conical form, and the corrugations b' b' radiating from its centre, as represented in the drawings. It is then secured, with its raised or conical side upward, to the lower end of the cylinder A by means of the usual interlapping seam a', substantially as represented in fig. 1, and, finally, the whole cylinder and bottom together (if of sheet iron) galvanized or coated with zinc in the usual well-known manner.

It will be seen that the conical corrugated form, described as given to the bottom, B, will greatly increase its strength, and resistance to injury from the falling lumps of ice, in supplying the cooler therewith.

I have applied a concavo-convex bottom, of cast iron, to the inner cylinder of a portable water-cooler for the same purpose, but find from experience that it is very liable to be broken by the falling lumps of the ice unless made so thick as to be both too costly and too heavy; and therefore have invented and applied the corrugated conical sheet-metal bottom herein described, and find that it effectually meets the requirements of durability, lightness, and inexpensiveness.

Having thus fully described my improvement, and shown its utility, what I claim as new, and desire to secure by Letters Patent, is confined to the following, viz:

I claim a sheet-metal water-cooler, having the bottom, B, of its inner cylinder, A, made of sheet metal, raised and corrugated substantially as described and shown, for the purpose specified.

JOHN L. HADDEN.
